(57) **CLAIM**

The ornamental design for an electric bicycle as shown and described.

DESCRIPTION

FIG. 1 is a front, right and top perspective view of an electric bicycle, showing my new design;

FIG. 2 is a rear, right and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion of FIG. 1 thereof;

FIG. 10 is an enlarged view of portion of FIG. 1 thereof;

FIG. 11 is an enlarged view of portion of FIG. 1 thereof; and,

FIG. 12 is an enlarged view of portion of FIG. 2 thereof. The dot-dash broken lines in FIGS. 1-2 and 9-12 indicate the boundaries of the enlarged views and are used for annotative purposes only. They do not limit or define the scope of the claimed design.
